UNITED STATES PATENT OFFICE

JAMES MILES, OF LOS ANGELES, CALIFORNIA.

AGITATING DEVICE.

Application filed April 14, 1923. Serial No. 638,009.

To all whom it may concern:

Be it known that I, JAMES MILES, a citizen of the United States, residing at Los Angeles, in the county of Los Angeles and State of California, have invented a new and useful Agitating Device, of which the following is a specification.

This invention relates to an agitating device which is intended to be especially useful for mixing paint or any other substance held in an open receptacle. Paint which has stood for some time in a receptacle usually becomes more or less solid or pasty at the bottom, and it is the common practice to mix the paint under such conditions with a stick or a similar implement. This gives unsatisfactory results. It has been attempted to use a device with blades for this purpose, and in such use it is necessary for the lowest blade to rest upon the bottom of the vessel containing the paint; and unless the device is held and rotated with its axis nearly vertical, the lowest blade will not maintain contact with the bottom of the vessel, and the device, therefore, operates inefficiently. The general object of this invention is to provide an agitating device of simple construction which will overcome these difficulties and which is constructed in such a way that the axis of rotation of the device need not be held exactly vertical; that is to say, my object is to provide a device of this kind which will operate effectively in spite of the fact that the axis of rotation may be considerably inclined from the vertical line.

A further object of the invention is to provide a device of this kind with simple means for effecting the rotation. Further objects of the invention will appear herein-after.

The invention consists in the novel parts and combination of parts to be described hereinafter, all of which contribute to produce an efficient agitating device.

A preferred embodiment of the invention is described in the following specification, while the broad scope of the invention is pointed out in the appended claims.

In the drawing:

Figure 1 is a side elevation of an agitating device embodying my invention and il-

lustrating a brace for rotating it with its chuck broken away and illustrated in cross-section; this view also indicates the manner in which the shaft of the agitator may be held in an inclined position and the dotted lines indicate the outline of the paint receptacle.

Figure 2 is also a side elevation, but showing the agitator provided with permanently attached means for rotating it.

Figure 3 is a view similar to Figures 1 and 2, but showing another form of the rotating means.

Figure 4 is a horizontal section through the shaft of the device near its lower end, but upon an enlarged scale.

In practicing the invention, I provide a shaft which is devoid of mechanical guiding means, but provided with means at its upper end to be seized in one's hands, operating to hold the shaft substantially upright and enable it to be rotated on its axis or on a vertical axis parallel with the axis of the shaft. In the embodiment illustrated in Figure 1, I provide a vertical shaft 1, the lower end of which is blunt so as not to penetrate the bottom of a metallic receptacle, and provided with one or more blades; the lowermost blade 2 is movably attached to the lower end of the shaft and preferably simply by means of a pivot 3 which permits the free pivotal movement of the blade on the shaft; that is to say, the axis of the pivot is transverse or at right angles to the axis of the shaft 1. Above this loose blade 2, I provide other blades, or simply another blade such as the blade 4, which if desired may be fixed to the shaft so as to extend at right angles thereto. However, I prefer to connect this blade 4 also by means of a pivot pin 5 and I prefer to mount this blade so that when it swings on its pivot it will swing in a plane transverse to or at right angles to the plane in which the blade 2 swings; in other words, blade 4 is disposed in a plane substantially at right angles to the blade 2. These blades are attached at their middle points, that is to say, at their center of gravity.

Any suitable means may be provided at the upper end of the shaft for rotating it,

for example, I may simply provide the upper end of the shaft 1 with a tang 6 constructed to fit into the chuck 7 of an ordinary brace 8 such as used by carpenters to operate an auger. This brace has a crank 9 with a grip 10 for rotating the shaft, and is provided at its upper end with a swivel-head 11, the axis of rotation of which is substantially in line with the axis of the shaft 1.

10 In the embodiment of the invention shown in Figure 2 the brace portion 12 of the device is constructed as an integral part of it, that is to say, the upper end of the shaft is merely bent to form a crank 13 and is provided with a swivel-head 15.

15 In the embodiment of the invention shown in Figure 3, I provide a single crank-arm 16 which is formed by bending over the upper end of the shaft, and I provide a swivel grip 20 17 just below this crank-arm. The outer portion of the crank has an upward extension or "wrist pin" 18 the upper end of which carries a swivel-head 19.

25 The lower ends of the agitators shown in Figures 2 and 3 may be constructed in substantially the same manner as that illustrated in Figure 1. In using the agitator, it is placed with its shaft in an upright position so that the lowermost blade 2 rests upon the bottom 20 of the paint receptacle, the outline of which is indicated by the dotted lines 21 in Figure 1. The shaft is then rotated, and in rotating it, it is unnecessary to maintain it in a true vertical position, that 30 35 is to say, the shaft could be held in an inclined position such as that indicated by the dotted lines 22. When held in an inclined position and rotated, it will be evident that the bottom blade 2 will rotate with the shaft 40 as it rotates and at the same time it will rotate on the axis of its pivot 3 so as to maintain itself substantially in engagement with the bottom of the receptacle.

45 In using the agitator when constructed as illustrated in Figure 3, if desired the hand which holds the grip 17 may be held stationary and the crank 16 revolved about it. This will give the same character of movement to the foot of the agitator as occurs in 50 55 the embodiment shown in Figure 1. But, if desired, the agitator may be operated by seizing the hand grip 17 and the swivel head 19 and then moving each of these parts through a small circle so that the real axis of rotation of the device will become a displaced vertical line such as the line 23 disposed between the shaft body and the wrist 18. This will give the foot of the agitator 60 65 a sweeping movement on the bottom of the receptacle and will increase the range of movement of the blades. At the same time, it will be evident that the blades will rotate as they move around in their circles or "orbits" and in case the body of the shaft 65 is not held in a true vertical position the

lowermost blade 24 of the device will constantly maintain itself in substantial engagement with the bottom of the receptacle.

By reason of the fact that the device has more than one blade, and also due to the fact 70 that the blades are pivoted at their middle points and in different transverse planes with respect to each other, they cooperate to maintain the lower end of the shaft in a more or less central position in the receptacle. 75 Where a device of this kind, but with a single blade at its lower end is used without any guiding means, the ends of the blade tend to hold themselves against the side of the receptacle so that as rotation takes place, 80 the blade simply "skates" around against the inner face of the wall of the receptacle. But with my construction, the end of the cross blade would engage the wall of the receptacle and prevent this. 85

If desired, the blades may have a slight pitch, giving them the effect of impellers to produce a slight upward movement of the paint from the bottom.

It is understood that the embodiment of the invention described herein is only one of the many embodiments this invention may take and I do not wish to be limited in the practice of my invention nor in my claim to the particular embodiment set forth. 90 95

What I claim is:—

1. An agitating device for mixing paints or the like in an open metallic receptacle, comprising a shaft having a blunt lower end adapted to engage without penetrating the bottom of the receptacle, and having means at its upper end for rotating it on its axis, and operating, when held in one's hands, to hold the shaft substantially upright, said shaft having a plurality of transverse blades attached at their middle points to its lower end, said blades being disposed in different transverse planes operating to maintain the shaft in a substantially central position as it is rotated in the receptacle, the lowermost blade being loosely mounted on the shaft, and operating to tilt with respect to the shaft, and maintain itself in engagement with the bottom of the paint receptacle in any upright inclined position in which the shaft may be held in rotating it. 100 105 110 115

2. An agitating device for mixing paint or the like in an open metallic receptacle, comprising a shaft devoid of guiding means, provided with means at its upper end for holding it up and rotating it on its axis, the lower end of said shaft being blunt to engage with, without penetrating, the bottom of the receptacle, and having a blade pivotally mounted at its center of gravity to the lower end of the shaft, the pivotal connection of the blade operating to enable the blade to rotate on the axis of the pivotal connection when the shaft is held and rotated in a position inclined to the plane of 120 125 130

the bottom of the receptacle, so as to maintain itself substantially in engagement with the bottom of the receptacle during the entire revolution of the shaft, and another ⁵ blade pivotally secured to the shaft above the first named blade and disposed in a plane transverse to the plane of the lower blade,

said blades cooperating to maintain the lower end of the shaft in a more or less central position in the receptacle.

10

Signed at Los Angeles, California, this 5th day of April 1923.

JAMES MILES.
